DESIGN FOR A COMBINED DIAL AND HANDS FOR A CLOCK OR SIMILAR ARTICLE

Charles C. Yotte, Jamaica, N. Y.

Application August 19, 1941, Serial No. 102,941

Term of patent 7 years

To all whom it may concern:

Be it known that I, Charles C. Yotte, a citizen of the United States, residing at Jamaica, in the county of Queens and State of New York, have invented a new, original, and ornamental Design for a Combined Dial and Hands for a Clock or Similar Article, of which the following is a specification, reference being had to the accompanying drawing, forming a part thereof, in which:

Figure 1 is a plan view of a combined dial and hands for a clock or similar article embodying my design.

Figure 2 is an edge view thereof.

I claim:

The ornamental design for a combined dial and hands for a clock or similar article, as shown.

CHARLES C. YOTTE.
